SIPHON BOTTLE HEAD

Harry J. Scott, San Francisco, Calif.

Application June 13, 1936, Serial No. 85,103

12 Claims. (Cl. 215—5)

This invention relates to siphon bottle heads for use on bottles containing gas charged liquids, such as "seltzer" water bottles, and has for its objects improved construction in such heads for dispensing the liquid through the head and for filling the bottle therethrough without causing the liquid to be unnecessarily broken up and thereby release an undue amount of its gas contents. Other objects are improved construction making for greater economy in manufacture of the heads and the labor in assembling the same. Still other objects and advantages will appear in the specification and drawing annexed hereto.

In the drawing, Fig. 1 is a vertical sectional view taken through an assembled head, valve therein, and part of the bottle, the valve being shown in open position.

Fig. 2 is an elevational view of the head secured on a bottle neck.

Fig. 3 is an elevational view of one half of the main body or shell of the head, the other half, not shown, being similarly formed to match the half shown for forming the body, said body being split.

Fig. 4 is a sectional view of the liquid conduit adapted to fit within the head.

Fig. 5 is an end elevational view of the liquid conduit looking at it from the discharge end of the conduit.

In detail, my siphon head comprises a split-hollow body of halves 1 and 2 formed when assembled to provide a through vertical bore enlarged and internally threaded at 3 at the lower end for engaging a threaded split band 4 on the neck 5 of a siphon bottle, the bore walls being shouldered at 6 above the threaded portion 3, and which bore then tapers inwardly and upwardly at 7 to a reduced diameter portion 9 at the upper end, and a passageway 10 extends laterally from the tapered portion through a nozzle member 11, that turns downwardly at its outer end to open outwardly and downwardly at the downwardly turned outer end of the nozzle member. An inwardly projecting flange 12 is formed around the passageway at the outer end of the nozzle member for a purpose later to be described.

Fitted within the head is a liquid conduit 13 that extends within the passageway from the outer end thereof to the portion 7 of the vertical bore of the body at its inner end, the inner end portion 14 being of generally bell shape, with the open end directed downwardly and an outwardly directed flange 15 being formed around the rim of the bell. This bell portion is formed to generally follow the contour of the tapered walls 7 of the vertical bore within the body, but slightly spaced

from the wall of the bore at the side opposite the juncture between the conduit 13 and bell portion thereof as indicated in Fig. 1. The flange 15 lies below the shoulder 6 and seats at its upper side against the lower surface of the shoulder. I also slightly thicken the upper wall of the bell portion of the conduit at 16 and the conduit itself is of oval cross sectional shape adjacent the bell portion, with its major axis horizontal, and gradually changes in cross sectional shape to circular at the outer end of the conduit, the passageway 10 being similarly shaped so the conduit is supported against the walls of the passageway throughout its length. The conduit 13 and bell portion 14 including the flange 15 is preferably of flexible, chemical resistant material, such as rubber. By chemical resistant, I mean a material adapted to resist the effect of carbonated liquids, such as seltzer water or the like.

Within the reduced bore portion 9, is mounted a cylindrical block 17 adapted to slide vertically therein, which block is horizontally slotted at 18 to receive a horizontally disposed cylindrical end 19 of an outwardly and downwardly curved handle 20 that projects outwardly of the body through an opening 21 in the body wall. Said handle is formed with oppositely outwardly extending pins 22 at opposite sides thereof adapted to revolvably fit in holes 23 formed in a pair of ears 24 formed respectively on each of the body halves.

A coil spring 25 is disposed within the bore 9 above block 17 and is adapted to react between block 17 and a cap 26 that fits over the body at the top of bore 9 and threaded engaging the body at the top to also assist in holding the halves tightly together.

Cap 26 is apertured at 27, and a disk 28 loosely fits across the lower side of the cap and is slidable in bore 9, against which cap the spring 25 engages at its upper end.

Spring 25, normally forces the block 17 downwardly on enlarged portion 16 of the conduit to force the upper wall of the conduit to tightly seat against the upper slightly rounded edge of a tubular member 29 of block tin, which member is formed with an outwardly projecting flange therearound below the upper end thereof 30 that fits below and against the flange 15 of the bell portion 14 of the conduit.

Fitted within the block tin member 29 at its lower end and cemented or otherwise suitably secured thereto in extension thereof is a vertical glass tube 31 that extends downwardly from the member to adjacent the lower end of the bottle,

but slightly spaced at its lower end above the bottom of said bottle and below flange 30 of the member 29 is a rubber gasket 32 that tightly fits between the upper edge of the bottle neck and flange 30, so that when the head is screwed onto the neck band 4 the head is tightly secured to the bottle and sealed against leakage at the neck.

Holding the lower end of the head together is a collar 33 threaded engaging threads 34 formed around the outer side of the head around that portion that is internally threaded at 3, and the halves of the body at the nozzle member are formed respectively with ears 35 that are held together by a screw 36 threaded into openings extending through the ears.

In assembling the head and various elements, I first insert one end of a cylindrical sleeve 37, made preferably of block tin, into the outer end of the conduit 13, the outer sides of the end within the conduit being tapered as indicated in Fig. 1. The sleeve is externally formed with an annular groove therearound midway of its ends, the end of the conduit abutting a shoulder formed around the sleeve slightly spaced from the groove toward the tapered end. The conduit and sleeve are then laid in one of the halves with the flange 12 of the nozzle member fitting within the groove on the sleeve, and the conduit lying in the passageway 10 and the bell end of the conduit in the bore of the main body with the flange 15 under shoulder 6. The handle member is laid in place with the end 19 in slot 18 in block 17 and the pin 22 in one of the openings 23, the block 17 being disposed in the portion 9 of the bore. The other half of the body is then clamped in place by the collar 33 and screw 36. The body is then screwed onto the bottle neck with washer 32 and members 29, 30 and 31 previously in place as described, thus tightly sealing the head to the bottle and supporting the member 29 with its glass tube 31 in place. The spring 25 is next inserted in the bore 9 and forced to compression by cap 26, which cap also coacts to hold the body halves together. Upon compression of spring 25 the top of the bell portion of the conduit is tightly sealed against the member 29 at the upper rounded edges thereof and the handle 20 is in the dotted position 20' as indicated in Fig. 1. Upon depressing the handle 20, to the full line position (Fig. 1) the pressure of the gas on the liquid in the bottle will force the liquid up tube 31 and will pass through the conduit, since the block 17 is raised to permit the upper wall of the bell portion 14 to lift.

It will be seen that the space between the tapered wall of portion 7 of the bore of the body and the wall of bell portion 14 provides for freedom of the bell portion to slightly buckle outwardly upon the block 17 moving downwardly to seat the upper wall of the bell portion against the band 29 and the thickened portion 16 permits considerable compression of the bell wall to insure a tight seal with member 29.

It will be seen from the foregoing that my improved construction enables the use of practically any metal for the head, as brass, bronze, aluminum, ferrous metals or alloys, since the liquid in the bottle during discharge is restricted solely to the glass, block tin and rubber, and the valve, being a part of the main conduit through the head, will open to permit a direct flow of liquid therethrough instead of causing the liquid to pass around ball or poppet valves or to be broken up in passing through variously ported valve members. Also when gas pressure is in the bottle, the rubber conduit is relieved of any unsupported

strain caused by the pressure that would tend to cause outward bulging of the conduit under such pressure. The provision of the split head construction enables a much more rapid assembly of the elements and disassembly thereof for replacing parts should replacements become necessary and the clamping of the body halves at the outer end of the nozzle member in itself secures the outer end of conduit 13 securely in position between the body halves and sleeve 37.

The sleeve 37, is provided not only to secure the conduit in position, but in filling the bottles, the sleeve 37 provides a hard fitting for engaging the filling nozzle on filling machines.

It is also to be noted that the underside of the nozzle member 11, is free of obstructions and is curved to fit the fingers of the holding hand of the operator, and the handle 20 in all positions extends in a downward and outward direction so as not to injure the palm of the operator in manipulating the valve to eject the liquid.

Having described my invention, I claim:

1. A siphon bottle head comprising a body divided into two parts each similarly recessed on their adjacent sides to coact for forming a bore through the body and the body at one end of bore being adapted for securement to the neck of a siphon bottle and the opposite end of the bore opening outwardly at a side of the body, means for removably securing the parts together, and a tubular liquid conduit comprising a tube of flexible material removably fitted within said bore for passing liquid therethrough to the outwardly opening end of the bore and means for distorting a portion of the walls of the tube to close the same to the flow of liquid therethrough.

2. A siphon bottle head comprising a vertically extending body including a nozzle member projecting laterally therefrom, said body being formed with an enlarged recess at its lower end formed for securing over the upper end of the neck of the bottle and a passageway formed in the nozzle member communicating between the recess and outside of the head at the outer end of the nozzle member, said head being vertically divided into two parts along vertical plane substantially bisecting the nozzle member and body, a flexible liquid conduit removably fitted within the passageway and means for distorting one of the walls of the conduit inwardly for closing said conduit to flow of liquid therethrough and means for holding the parts together.

3. In a construction as defined in claim 2, said conduit being formed with an annular outwardly projecting flange positioned within the head and engaging the bottle neck when the head is assembled on a bottle.

4. In combination, a siphon bottle head comprising a body formed with a downwardly opening enlarged recess on its lower side and a nozzle member projecting laterally from a side of the body said nozzle member being formed with a through bore communicating between the recess at its inner end and outside the head at the outer end of the nozzle member, a siphon bottle mounting the head with the neck of the bottle at the mouth thereof secured within said recess, an annular valve seat concentric with the bottle neck positioned between the upper edge of the neck and body within said recess, a liquid conduit within the bore of the nozzle member having a portion formed integrally therewith projecting into said recess and over said annular seat, the portion of the conduit over the seat being flexible and adapted to move toward and away from the

- seat for opening and closing the opening in the annular seat to flow of liquid therethrough to the conduit.
5. In a construction as defined in claim 4, said seat having a tubular extension in axial alignment therewith projecting downwardly therefrom into said bottle, and the conduit being secured at its opposite outer end to the nozzle member at a point adjacent the outer end of the 10 nozzle member.
10. In a construction as defined in claim 4, means accessible from outside the body for moving said end of the conduit toward said seat and for releasing said end for movement away from 15 the seat.
15. In a construction as defined in claim 4, an annular horizontal flange projecting outwardly around said seat and an annular resilient flange on said conduit within said recess formed to engage over said outwardly projecting flange and between the body and outwardly projecting flange, a yieldable washer below said outwardly projecting flange between the upper edge of the bottle neck and outwardly projecting flange, said 20 washer, outwardly projecting flange and flange on the conduit being adapted to coact for forming a seal between the body and bottle against leakage.
25. A siphon bottle head comprising a vertically bisected vertically extending body portion forming halves separably joined together along the line of division, said halves being similarly recessed on adjacent sides for forming a vertically extending open ended bore therethrough when the halves are together and a side of said body being provided with a laterally directed open ended passageway communicating at its inner end with said bore and opening outwardly of the body at its outer end, a one piece conduit secured 30 within said passageway and a valve and valve actuating means arranged and adapted to close the conduit to flow of liquid therethrough from its inner to its outer end, said valve and valve actuating means all being mounted within said bore whereby they are accessible from a lateral side of one of the halves when the halves are separated, and means for securing the halves together in assembled relation.
35. In a construction as defined in claim 8, said valve including an annular valve seat and a member movable for seating thereon, said annular valve seat being separate from the conduit for replacement of the conduit independently thereof, and the walls of said passageway in close engagement with the outer sides of the conduit for firmly supporting the conduit and the line of division of said body vertically bisecting said passageway.
40. A siphon bottle head comprising a vertically bisected body forming halves separably joined together along the line of division, said halves being similarly recessed on adjacent sides to form an upper, vertically extending bore in the upper portion of the body and a vertically extending bore in the lower portion of the body when the halves are together, said bores connecting at adjacent ends and the upper bore be- 45
